UNITED STATES PATENT OFFICE.

WILLIAM M. GROSE, OF KENOSHA, WISCONSIN, ASSIGNOR OF ONE-HALF
TO MORGAN GAFFNEY, OF KENOSHA, WISCONSIN.

BED-BOTTOM.

No. 837,923.

Specification of Letters Patent.

Patented Dec. 11, 1906.

Application filed March 30, 1906. Serial No. 308,959.

To all whom it may concern:

Be it known that I, WILLIAM M. GROSE, a citizen of the United States, residing at Kenosha, in the county of Kenosha and State of Wisconsin, have invented a new and useful Bed-Bottom, of which the following is a specification.

This invention relates to bed or couch fabrics for use in the formation of the bottoms thereof; and the object of the invention is to provide an elastic fabric of this character formed of a novel arrangement of wires and springs, none of said wires being weakened at any point between their ends by eyes or coils, such as are ordinarily employed in fabrics of this character.

The invention consists of a frame on the ends of which are disposed helical springs connected by straight wires. Interposed between these wires are intermediate wires which are zigzagged and are movably connected to the straight wires by clasps provided for that purpose. The ends of these intermediate wires are fastened to the springs.

25 The invention also consists of certain other novel features of construction and combinations of parts, which will be hereinafter more fully described, and pointed out in the claims.

30. In the accompanying drawings is shown the preferred form of the invention.

In said drawings, Figure 1 is a plan view, and Fig. 2 is a transverse section.

Referring to the figures by numerals of reference, 1 1 are side rails connected at their ends by cross-wires 2, provided with upstanding flanges, in which are disposed apertures 3. Each aperture receives the hooked end 4 of a helical spring 5, provided at its other end with a downwardly-extending hook 6. The springs upon the two end rails 2 are connected by straight wires 7, having eyes 8 at their ends which engage the hooks 6 and hold

the springs constantly under tension. Intermediate wires 9 are interposed between the wires 7 and are zigzagged from end to end, their angles 10 being loosely connected to the adjoining wires 7 by means of broad metal clasps 11, each formed of a strip of metal having downwardly-extending hooks 12 at its ends, which embrace the wires and prevent them from becoming displaced. The

ends of the intermediate wires have eyes 13, which engage the hooks 6; but between these ends said wires are absolutely free of loops or eyes of any form. Where the intermediate wires are bent, they are engaged by broad clasps, and said wires are therefore not weakened to any extent, and as a result the entire fabric is of the same strength as though it were formed only of straight wires. Considerable importance is attached to the fact that no intermediate eyes or loops are formed by the wires 9, because such a construction tends to weaken the wires and lessen the durability of the fabric. 55 60 65

Although I have shown and described the use of broad metal clasps for the purpose of binding wires together at points between their ends, it is to be understood that, if preferred, wire clasps may be substituted therefor. 70

What is claimed is—

1. The combination with a frame having
springs connected to the ends thereof; of
straight parallel wires interposed between
and connected at their ends to the springs,
zigzag intermediate wires interposed between
the straight wires and connected at their ends
to the springs, and clasps mounted upon the
straight wires and having hooked ends en-
gaging the angle portions of the intermediate
wires. 75 8c

2. The combination with a frame having 85
springs connected to the ends thereof; of straight parallel wires interposed between and connected at their ends to the springs, zigzag intermediate wires interposed between the straight wires and connected at their ends to the springs, and clasps mounted upon the 90 straight wires and each having a hook engaging the angle portion of one of the intermediate wires.

3. The combination with a frame having upstanding end rails, helical springs engaging the end rails and having downwardly-extending hooks; of straight wires interposed between the springs and terminating in eyes engaging the hooks, zigzag intermediate wires interposed between the straight wires and having eyes at their ends engaging the hooks, and clasps mounted upon the straight wires and each having a hooked end engaging the angle portion of an intermediate wire. 95 100

2
4. A fabric for bed-bottoms consisting of straight parallel wires, zigzag intermediate wires interposed between the straight wires, and clasps mounted upon the straight wires
5 and engaging the angle portions of the intermediate wires.

In testimony that I claim the foregoing as

my own I have hereto affixed my signature in the presence of two witnesses.

WILLIAM M. GROSE.
